SOUND PRODUCING ATTACHMENT FOR
ROLLER SKATESClarence E. Karst, Cincinnati, Ohio, assignor to
The Brunhoff Manufacturing Company, Cincinnati, Ohio, a corporation of Ohio

Application September 16, 1936, Serial No. 101,120

7 Claims. (Cl. 116—61)

This invention relates to roller skates. More particularly, the invention is directed to the combination, with roller skates of sound producing instrumentalities operable by foot movement of the skates.

It is an object of the present invention to provide the combination of a roller skate and a simple, sturdy, sound producing apparatus.

Another object of the invention is to provide an alarm mechanism embodied in a roller skate of the conventional type, and controlled in operation by the skater, through foot movement, during movement of the skate.

Still another object of the present invention is to provide a novelty apparatus which is universal in respect to attachment to roller skates of the conventional variety, by mechanical adjustments and operations, simple enough to be understood and performed readily by children.

Further objects and advantages will appear in the following specification, and in the drawing in which:

Figure 1 is a side view of a skate equipped according to the present invention.

Figure 2 is a side view similar to Figure 1, but showing the skate in the position for producing sound.

Figure 3 is a rear view of the skate shown in Figure 1.

Figure 4 is a sectional view taken on the line 4—4 of Figure 1.

Figure 5 is a sectional view taken on the line 5—5 of Figure 3.

Figure 6 is a perspective view showing the sound producing attachment of the present invention.

Briefly stated, the present invention comprises the combination with a roller skate, of sound producing apparatus having a ground wheel normally out of the range of the tread or ground level of the roller skate, but adapted to be actuated by friction contact with the ground during canted movement of the skate. Otherwise stated, the invention comprehends a roller skate having a sound or noise producing equipment adapted to be operated through a ground wheel positioned for actuation by canting of the skate from normal tread position.

During the period of actuation of the ground wheel the sound apparatus is driven or operated frictionally either to sound alarm, to signal or to satisfy the natural tendency of children to enjoy the noise or sound. The type of sound produced by the device, its tone quality and its volume are determined initially by the type of instrumen-

tality selected, e. g. bell, siren, or similar means. The volume of sound thereafter produced by the instrumentality is controlled largely by the speed of the skater.

The drawing illustrates a preferred embodiment of the invention in which a bell is utilized as a primary sounding instrument. This bell is struck during movement of a rotary striker operated by and during actuation of a ground wheel journaled in a stationary tail or bracket piece, with its tread out of ground contact, but movable into ground contact through alteration of the position of the skate from normal position.

Referring to the drawing more particularly, the skate is indicated generally at 1. This skate, which may be of the usual design and construction, comprises a foot plate 2, from which journal brackets 3 extending downwardly to carry axles 4—4 on which roller wheels 5 rotatively are mounted.

The axles of the skates preferably are housed within sleeves 6 engaging the journal brackets 3, and are provided with shoulders 7 in the conventional manner of construction. One of these axle shoulders 7 preferably is used as the abutment 25 for mounting the sound producing equipment. The rest of the elements of the skate proper follow the usual lines of construction, and need not be described in detail for this reason.

One form of sound producing apparatus constructed in accordance with the present invention for universal attachment to any of the types of roller skates available at present is indicated generally at 8. The combination of the skate with this apparatus preferably is as follows:

A tail piece or bracket plate 9 is provided with a bore 10 at one extremity for engagement over an axle 4 of the skate proper, intermediate the shoulder 7 and the wheel 5, of the axle on which the bracket is to be mounted. The bracket plate 9 is disposed over the axle so as to abut the sleeve shoulder 7. The bracket plate at the locality adjacent the bore 10 preferably is of reduced dimensions, to clear the extremities of the journal bracket 3.

A plurality of clinch lugs or teats 11 are disposed concentrically around the bore 10 preferably in slightly spaced relation. These teats are adapted to bite into the annulus at the shoulder 7 when the tail piece engages the axle, to provide 50 positive locking of the tail piece in the intended position, as the nut 12, (which conventionally is used to hold the wheel 5 in position on the axle) is tightened.

These teats 11 preferably are positioned to pro-

- vide biting surfaces extending conically toward the aperture 10, first to facilitate centering of the tail piece over the axle, and onto the annulus of the shoulder, and secondly, to facilitate positive locking of the tail piece to sleeves or shoulders of different diameters. Thus, the series of conical teats shown in Figure 5, which concentrically surround the aperture 10, in combination with corresponding indentures which these teats form in the shoulder annulus during tightening of the nut 12, provide a mounting which is positive, universal and self-centering in respect to sleeves of counter-turned shoulder annuli of varying diameter. It is obvious that this mounting of the bracket plate to a conventional skate is simple to perform, and requires the use of no more tools than are required to remove and replace the wheels of the skates themselves. On the other hand, however, other suitable means for attaching the sound equipment to the skate proper may be substituted for the means disclosed. Thus the sound equipment may extend fore or aft the skate in position suited to actuation of the apparatus by canting movement of the skate from normal tread position.
- The tail piece 9 preferably is stiffened with a marginal flange 13, and a bell 14 is mounted within this flange in a position spaced from the mounting bore 10 for clearance purposes. The bell threadedly is carried on a stud 15 extending rigidly from the tail piece 9. The tail piece 9 is mounted on the skate so that the bottom portion of the marginal flange 13 clears the ground during normal skating movement.
- A bracket clip 16 extends from the tail piece 9 in spaced relation on the side of the tail piece opposite the bell, to carry a stud or jack shaft 17 on which a ground wheel 18 rotatively is mounted. The ground wheel, which preferably is rubber tired, as at 18a, is journaled at the tail piece with its tread out of ground contact, but adapted to be grounded for traverse and actuation by alteration of the position of the skate, in the manner shown in Figure 2.
- The shaft 17 over which the ground wheel 18 is mounted preferably is carried in slots 19—19 in the clip support 16 and in the tail piece 9 in corresponding locations. A stub shaft 20, driving the sound equipment indicated generally at 21, is journaled for rotation in the bracket clip 16 and in the tail piece 9 for frictional engagement thereof by the ground wheel during its period of movement. When the skate is canted, the shaft 17 moves to the upper limiting extremity of slots 19—19 to limit canting movement of the skate.
- Thus, in the arrangement which is shown, the ground wheel is brought into frictional contact with the tread of the skate when the forward portion of the skate is tilted upwardly by foot movement of the skater. During this tilting movement the ground wheel first comes into contact with the tread, then the play in the slots in which the shaft 17 is disposed is taken up, and the ground wheel then frictionally drives the stub shaft 20 actuating the sound producer 21.
- It is preferable to position the slots in the bracket clip and tail piece angularly with respect to the longitudinal axis of the support clip 16 in which latter the stub shaft is disposed. This angular position through which the axle 17 is moved causes the ground wheel 18 bindingly to engage the stub shaft 20 rather than at right angles. This arrangement reduces the amount of slippage of the stub shaft in respect to the ground wheel and provides a much more positive friction

drive. A suitable wedging action is provided in the relationship of slot to stub shaft shown in Figure 1.

The stub shaft 20 extends through the tail piece 9 to carry spur gear 22 which meshes with the spur gear 23 mounted on shaft 15 on which the bell 14 is carried. A rotary type striker 24 is mounted for rotation with the spur gear 23. During rotation of the striker hammer elements 25 centrifugally are thrown into contact with a lug 26 extending inwardly from the bell 14.

When the skate of the present invention is in the normal tread position the ground wheel 18 clears the tread and the sounding device is inoperative. At the will of the skater the toe is lifted by rocking movement on the back wheel of the skate for actuation of the ground wheel, and sound is produced as long as the skate remains in this position. It should be understood, of course, that the sound equipment may be mounted at the front of the skate rather than at the rear in which instance, the actuation of the device is controlled by forward rather than rearward canting motion.

Having described my invention, I claim:

1. The combination, with a roller skate, of a bracket plate fixed to the skate, a ground wheel journaled on the bracket plate with its tread out of ground contact and adapted to be grounded upon canting of the skate, and a sound producing apparatus mounted on said bracket and having a shaft frictionally contacting the tread of the ground wheel for actuation thereby.

2. The combination, with a roller skate, of a bracket plate fixed to an axle of the skate, a ground wheel journaled on the bracket plate with its tread out of ground contact but adapted to be grounded upon canting of the skate, and a sound producing apparatus mounted on said bracket plate and having a shaft frictionally contacting the tread of the ground wheel for actuation thereby.

3. A sound producing attachment mounted on a roller skate having an axle counterturned to provide a shoulder comprising, a bracket plate having a bore, a plurality of teats spaced concentrically around said bore to provide locked engagement of said plate with said axle of said roller skate, a ground wheel mounted for rotation on said bracket plate with its tread extending beyond the margin of the same, and a sound producing instrumentality carried by said bracket plate and having a driving shaft frictionally engaging the tread of said ground wheel.

4. A sound producing attachment mounted on a roller skate having an axle counterturned to provide a shoulder comprising, a bracket plate having a bore, a plurality of teats spaced concentrically around said bore to provide locked engagement of said plate with said axle of said roller skate, a ground wheel mounted for rotation on said bracket plate with its tread extending beyond the margin of the same, and a sound producing instrumentality mounted on said bracket plate opposite said ground wheel and having a driving shaft, journaled in said bracket plate, frictionally engaging the tread of said ground wheel.

5. A sound producing device for attachment to a roller skate for actuation by canting of said skate from normal tread position, said device comprising a bracket plate having a bore for engagement with an axle of said skate, and having a stiffening flange, a ground wheel mounted for

rotation on said bracket plate with its tread extending beyond said flange for driving, and a sound producing instrumentality, mounted within said flange, and having a driving shaft frictionally engaging said ground wheel.

5. A sound producing attachment for a roller skate comprising, a bracket plate having a bore for engagement with an axle of said roller skate, a clip support extending from said bracket plate 10 in spaced relation therewith, a shaft carried in said plate and clip support, a ground wheel journalled on said shaft, and a sound producing instrumentality carried by said bracket plate.

and having a driving shaft frictionally engaging the tread of said ground wheel.

7. The combination, with a roller skate having an axle counterclockwise to provide an abutment shoulder, of a bracket plate having a bore for engagement with said axle of said skate, a plurality of teats spaced concentrically around said bore, and indented in said shoulder, a ground wheel journalled on said bracket plate and sound producing apparatus having a shaft frictionally 10 engaging the tread of said ground wheel, the sound producing apparatus carried by said bracket plate.

CLARENCE E. KARST.
